UNITED STATES PATENT OFFICE.

WILLIAM M. SMEATON, OF CAMDEN-TOWN, COUNTY OF MIDDLESEX,
ENGLAND.

APPARATUS FOR CASTING TRAPS.

SPECIFICATION forming part of Letters Patent No. 389,019, dated September 4, 1888.

Application filed March 2, 1887. Serial No. 229,492. (No model.) Patented in England October 2, 1879. No. 3,952.

To all whom it may concern:

Be it known that I, WILLIAM M. SMEATON, of Camden-Town, in the county of Middlesex, England, have invented a new and Improved 5 Apparatus for Casting Traps, (which has been patented in Great Britain, dated October 2, 1879, and numbered 3,952,) of which the following is a full, clear, and exact description.

My invention has for its object to provide an 10 improved apparatus for molding traps for water-closets and for other purposes, whereby a complete trap may be cast in one piece without seam or joint.

The invention consists in a novel construction 15 and combination of parts, as hereinafter fully described, and particularly pointed out in the claims.

Reference is to be had to the accompanying drawings, forming a part of this specification, 20 in which similar letters of reference indicate corresponding parts in all the figures.

Figure 1 is a front elevation, partly in section, of a trap-molding apparatus embodying my improvements. Fig. 2 is an end elevation 25 of the same, showing the core and part of the frame in section. Figs. 3 and 4 are enlarged detail side and end views of the core. Fig. 5 is a longitudinal section taken through the center of the core. Fig. 6 is a cross sectional 30 view on the line *w w*, Fig. 5. Fig. 7 is a cross-sectional view on the line *x x*, Fig. 5. Fig. 8 is a plan of the core, partly in section on the line *y y*, Fig. 5. Fig. 9 is a section plan view of the same on the line *z z*, Fig. 5.

35 C designates legs or trestles, on which the T-shaped bed-plate or frame D rests.

E designates two blocks or carriages mounted to slide on the cross-arm of the T-shaped frame, and F a block or carriage mounted to 40 slide on the angled arm of the T-frame. The three sliding blocks or carriages E E F can be brought toward the angle of the T-frame or withdrawn therefrom by means of handle-levers G, pivoted at their lower ends to brackets *a*, fixed at the end of each arm of the T-frame and connected with the blocks or carriages by links *b* and pivots *c*, as shown.

On each sliding block or carriage E is secured a half-section, H, of the outside mold, 45 as by means of bolts *d*, the interior of said mold, formed by the two sections H, when

brought together, having the form of the exterior of an ordinary D-trap.

A collar, J, is fixed to or formed integrally with the rear sliding block or carriage, F, and in said collar is held adjustably, by means of the set-screw *f*, the hollow cylindrical end of the rear outside section, *e*, of the mold. The section *e* serves to close what we may term the "outflow" end of the mold, and to it is attached or with it formed the lower section, *g*, of the body of the core. The section *g* is made hollow, and in it and a plumber block, *t*, fixed within the hollow section *e*, is mounted to turn the horizontal screw *h*, on which a movable nut, *i*, works. To the nut *i* is pivoted by a joint, *k*, the rear end of a link, *j*, the forward end of which is pivoted by a pin, *l*, to the swinging section *m* of the core, hinged to the end of section *g* by a pin, *n*. The screw *h* is turned by a crank-handle, *h'*, secured to its rear end.

o and *p* designate loose sections of the core resting upon the sides of section *g*. The rear upper core-section, *o'*, is hinged to the rear 75 mold-section, *e*, by a joint, *r*, and is pressed upward into its proper position by a spring, *s*, secured to the plumber-block *t*.

For forming the inflow-pipe of the trap I employ a core-section, *u*, which I term the 80 "mandrel." The mandrel is arranged to move vertically in guide-apertures *v v*, formed in the bed-plate D, and can be given such movement by means of a handle-lever, K, pivoted at its rear end by a pin, *w*, to a bracket projecting from the bottom of the frame D, and connected with the lower end of the mandrel by a link, *x*, and pins *y z*, as shown. The handle-lever K can be adjusted to hold the mandrel in any desired position by means of 85 a set-screw, *b'*, engaging a segmental bracket-arm, *a'*, riding in a slot or keeper on the lever. On the top of the mandrel the small loose core-sections *e' f'* are placed. Loose sections *c' d'* rest on the core-sections *o* and *p*, 90 respectively, and on top of all is placed the loose section *g'*. The hinged section *o'* fills the space between the sections *c'* and *d'* and *o* and *p*, and thus completes the core, which is the exact shape and size of the interior of the 95 D-trap. A wedge-shaped opening, *i'*, is made in the top of the mold by suitable recesses in

the meeting mold-sections H H, and leads into the casting-space between the mold and core. The mandrel *u* and the loose sections *e*, *f*, *e'*, and *d* interlock each other, as shown 5 in Fig. 8; and to further prevent the various parts of the core from shifting upon one another dowel-pins or other suitable devices may be employed.

To form a casting I first build up the core, 10 as described, and bring the mold-sections together, as shown in Fig. 1 and 2. The molten metal, as lead, is then poured into the opening *i*', and forms when set a casting of the desired shape and thickness, a solid section of 15 the same being shown in Figs. 1 and 2. To remove the casting I withdraw the mandrel *u* a short distance by means of the lever *K*, after which I lower within the core the swinging section *m* by means of the screw *h* and handle *h'*. The rear sliding block, *F*, is then withdrawn, carrying with it the mold-section *e* and core-sections *g*, *m*, and *c'*, the spring *s* yielding to allow the section *o'* to issue from the trap-outlet. The mold-sections H H are then drawn 20 back by means of the levers *G* *G*, when the casting can be lifted off the mandrel *u*. The loose core-sections *g'*, *e'*, *f'*, *c'*, *d'*, *o*, and *p*, which are left in the casting, can then be removed by hand, leaving the trap entire, without seam or 25 joint.

In some cases I may modify the described arrangements by dispensing with the screw *h* and spring action *s*, in connection with the core-sections *m* and *o'*, and dividing the sections of that part of the core into more sections, when the whole of the core, except the mandrel *u*, may be removed by hand from the casting. In some cases, also, I may withdraw the core-mandrel by hand directly where rapidity of action is not required.

Having thus fully described my invention, what I claim as new, and desire to secure by Letters Patent, is—

1. In an apparatus for molding traps, a section 45 of a core consisting of two movable sections

at approximately right angles to each other, two hinged sections carried by one of the movable sections, and loose sections on the said movable sections, substantially as described.

2. The combination, with the movable mold-section *e*, carrying the core-section *g*, the movable core-section *u*, and the superposed core-sections on the sections *g* and *u*, of the hinged section *m*, pivoted within the section *g*, and means for operating said hinged section, substantially as described. 50

3. The combination, with the frame of the apparatus, of blocks or carriages mounted to slide thereon, which blocks carry the mold-sections, a core composed of detachable sections, one of which forms a mandrel arranged to enter the mold, an additional sliding block or carriage supporting another of the core-sections, and means for moving the mold and core section carriages, substantially as specified. 60

4. The combination, with the movable mold-section *e*, carrying the core-section *g*, the movable core-section *u*, and superposed core-sections on the sections *g* *u*, of the hinged section *m* in the section *g*, the screw *h*, nut *i* on the 70 screw, and the link *j*, pivoted to the nut and to the hinged section, substantially as described.

5. The combination, with the frame *D*, of the carriage *F*, mounted to slide thereon, the core-section *e*, supported thereby, the additional detachable core-sections, the mandrel *u*, guided in the frame *D*, and devices for operating the carriage *F* and mandrel *u*, substantially as specified. 75

6. The combination, with the movable mold-section *e*, of a sectional core, the section *o'* of which is hinged to the said mold-section and pressed upward against the adjacent sections by the spring *s*, secured in the said mold-section, substantially as described. 80
